(57) **CLAIM**

The ornamental design for a game target, as shown and described.

DESCRIPTION

FIG. 1 is a front elevational view of a game target showing my new design;

FIG. 2 is a rear elevational view thereof;

FIG. 3 is a side view, taken from the left side of FIG. 1, the right side view being a mirror image thereof:

FIG. 4 is a top plan view thereof;

FIG. 4 is a top plan view thereof;

FIG. 6 is a perspective view of the game target of my new design.

The broken line showing a toss ball assembly in FIG. 6 is for illustrative purposes only and forms no part of the claimed design.

1 Claim, 6 Drawing Sheets

FIG. 1

FIG. 2

FIG. 3

FIG. 4

FIG. 5

FIG. 6
